Design No. 20,623, dated March 24, 1891.

UNITED STATES PATENT OFFICE.

GEORGE J. STENGEL, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,623, dated March 24, 1891.

Application filed February 16, 1891. Serial No. 381,711. Term of patent 3½ years.

To all whom it may concern:

Be it known that I, GEORGE J. STENGEL, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of the body A and border B. The body A consists of a landscape effect consisting of a foreground of grass, flower, and shrub forms, a portion resembling water, and a background of tree, flower, and leaf forms having a vista showing forms resem-

bling the stars and moon upon a cloudy effect. The border B consists of an inner margin of grass forms, a middle portion of shrub and flower forms, and a portion resembling water 25 in the foreground, and a background of shrub, tree, and leaf forms protruding into a cloud-like effect with containing forms resembling the stars and the moon.

What I claim as new, and desire to secure 30 by Letters Patent, is—

1. The design for carpets, consisting of the body A, substantially as shown.
2. The design for carpets, consisting of the border B, substantially as shown.
3. The design for carpets, consisting of the body A and the border B, substantially as shown.

GEORGE J. STENGEL.
